FRANK H. FRENCH, OF PRESTON, IOWA.

TANDEM DISK HARROW.

1,399,607.

Specification of Letters Patent. Patented Dec. 6, 1921.

Application filed June 12, 1920. Serial No. 388,520.

To all whom it may concern:

Be it known that I, FRANK H. FRENCH, a citizen of the United States of America, and resident of Preston, Jackson county, Iowa, have invented a new and useful Tandem Disk Harrow, of which the following is a specification.

The object of this invention is to provide an improved construction for tandem disk harrows.

A further object of this invention is to provide improved means for connecting a trailer harrow to a leader harrow.

A further object of this invention is to provide improved means for utilizing power of a tractor to simultaneously and uniformly alter the angular relation of the gangs of a leader and a follower harrow.

A further object of this invention is to provide means in a harrow equipped for power operation of its gangs, for selectively changing either of the gangs by manual operation.

A further object of this invention is to provide an improved construction for a bearing for disk harrows with particular relation to the means for supplying lubricant thereto.

My invention consists in the construction, arrangement and combination of elements hereinafter set forth, pointed out in my claims and illustrated by the accompanying drawings, in which—

Figure 1 is a plan of my improved harrow and Fig. 2 is a side elevation of the same. Fig. 3 is an enlarged vertical section on the indicated line 3—3 of Fig. 1. Fig. 4 is an enlarged section on the line 4—4 of Fig. 2. Fig. 5 is a perspective illustrating a rock shaft employed for shifting the angular relation of the gangs of the rear harrow.

Fig. 6 is a plan illustrating a special bearing employed, the upper bearing member being removed. Figs. 7 and 8 are cross-sections through the complete bearing, taken respectively on the lines 7—7 and 8—8 of Fig. 6. Fig. 9 is a cross-section through both bearing members, taken on the line 9—9 of Fig. 6.

Fig. 10 is a side elevation illustrating a lever which may be employed for manual operation of the rear disk gangs in lieu of the power operated means for shifting the same.

This invention relates to and is an im-

provement on the invention illustrated, described and claimed in Letters Patent of the United States Number 1,337,448 granted to me April 20, 1920, to which reference hereby is made. Many features of the leader 60 disk harrow herein shown are also illustrated and described in Letters Patent of the United States Number 1,286,986 granted to me December 10, 1918.

The leader disk harrow consists, generally, of a relatively long main frame, designated generally by the numeral 10, having a length corresponding substantially to the combined lengths of the disk gangs or units 11, 12. Evener bars 13, 14 are pivoted at 70 their centers to and on opposite sides of the center of the main frame 10 and have their outer ends pivotally connected, by means of links 15, 16 respectively, to extreme outer end portions of the respective disk gangs. 75

The trailer harrow has two disk gangs, designated generally by the numerals 17, 18, which are arranged in staggered relation and oppositely dished relative to the disks of the forward harrow. At the extreme 80 outer end portions of the gangs 17, 18, preferably between the two outermost disks thereof, are boxings 19, 20, shown in detail in Figs. 6 to 9 inclusive and hereinafter described at length. For the present it is sufficient to say that each of said boxings is formed with a horizontal bearing to journal an axle of a disk gang, and with a forward projection 21 formed with a vertical bearing 22. A cross frame bar 23 is formed 90 of two spaced parallel members suitably secured together, is arranged above the disk gangs 17, 18, and has its end portions turned downwardly adjacent the boxings 19, 20. In the downturned end portions of the cross 95 frame bar 23 are secured spindles 24, 25, vertically arranged and projecting at both ends from said frame bar. The lower projecting ends of the spindles 24, 25 are swiveled in the vertical bearings 22 of the forward projections of the respective boxings 19 and 20. The cross frame bar 23 provides a means for connecting the disk gangs 17, 18 and preventing their separation in use. An

evener bar 26 is transversely arranged in 100 front of and substantially parallel with the cross frame bar 23. The evener bar 26 has its ends hooked or recurved rearwardly at 26^a and lying in the same horizontal plane as the body portion thereof. Draft links 27, 110

28 are arranged substantially horizontally and have their rear ends pivoted on upwardly projecting portions of the spindles 24, 25, and their forward ends converging 5 somewhat and overlying end portions of the evener bar 26 and pivoted to bolts 29, 30 extending vertically therethrough. Other draft links 31, 32 are pivoted at their rear ends to lower end portions of the spindles 10 24, 25, are inclined upwardly throughout portions of their lengths, and have their forward end portions bent into horizontal planes spaced below the draft links 27, 28. The forward end portions of the lower draft 15 links 31, 32 engage the lower surface of the hooked end portions of the evener bar 26 and are pivoted on the bolts 29, 30. Forward portions of the draft links 27-31 and 28-32 also are connected by bolts 33, and 20 hammer-strap braces 34 extend from said bolts to the bolts 29 and 30, the last named bolts extending materially above the evener bar 26. The hooked portions of the evener bar 26 are embraced between the parallel 25 portions of the draft links 27-31 and 28-32 to prevent tilting of said bar under strain. Draft links 35, 36 are provided to connect end portions of the evener bar 26 to the stub tongue 37 of the forward harrow, said draft links preferably converging substantially on the same angles assumed by the rearward draft links, so that they are substantially in line, on each side of the device. Each draft link 35, 36 preferably 30 is composed of two flat bars arranged with their greater transverse dimension vertically, the forward portions of which are side by side and bolted rigidly together, as by bolts 38. Near their rear ends the bars 35 composing each of the draft links 35, 36 diverge to form vertically arranged forks, the rear portions of which are formed with eyes pivoted on the bolts 29 and 30. The upper members of the forks are pivoted on 40 upper end portions of the bolts 29 and 30, above the braces 34, and the lower members of the forks are pivoted on lower ends of said bolts, below the lower rear draft links 31 and 32. The general form of the forward draft links 35, 36 is arched, whereby they are carried over the forward disk gangs 11, 12, the forward end portions inclining downwardly. A plate 39 is arranged transversely of and rigidly clamped to the stub 45 tongue 37 and projects at both ends therefrom, and U-clips 40, 41 are swiveled on vertical axes on end portions of said plate. Forward ends of the foremost draft links 35, 36 enter the clips 40, 41 and are pivoted 50 therein on transversely arranged bolts 42. Thus means is provided for transferring the draft force from the stub tongue of the forward harrow to outer end portions of the trailer harrow, and for bridging the draft 55 devices over the harrow devices, the ar-

angement being such that the two harrows of the tandem may independently turn laterally of the line of advance.

The stub tongue 37 of the forward harrow preferably is composed of two angle 70 irons slightly spaced apart and arranged with their vertical flanges projecting upwardly at their outer margins. A draw bar 43, preferably formed of T iron, is mounted in the seat formed by the angle bars of the stub tongue 37 and is adapted for limited sliding movement therein. The draw bar 43 is adapted to be attached in any suitable manner to a tractor employed to furnish motive power for the harrows. A yoke-shaped shifting lever 44 is arranged with its closed end uppermost, straddles the stub tongue 37 at the rear of the plate 39, and is pivoted between its ends on said stub tongue by means of bolts 45. Links 46, 47 are pivoted at opposite sides of the upper end of the yoke lever 44 and extend rearwardly and downwardly and on divergent planes to points beneath outer end portions of the evener bar 26. Rock shafts 48, one of which 80 is shown in Fig. 5, are arranged beneath the evener bar 26 and on opposite sides of the center thereof and are journaled for oscillation in U-clips 49 carried by said bar. Each rock shaft 48 is formed with crank 85 arms 50, 51 at its ends extending downwardly in different planes, and the innermost crank arms 50 are pivotally connected, by means of links 52, 53 respectively, to inner end portions of the gangs of the rear 90 harrow, said links being pivoted at their rear ends to boxings 54, 55 carried by said gangs. The outermost crank arms 51 of the rock shafts 48 are pivotally connected to rear end portions of the links 46, 47 respectively. Thus it will be seen that oscillation of the yoke lever 44 will, through the links 46, 47, cause a rocking movement of the shafts 48 and through the links 52, 53, effect an adjustment of the angularity of the rear 100 gangs 17, 18 relative to the line of draft, the gangs articulating on the axes of the spindles 24, 25. Links 56, 57 are arranged on opposite sides of the stub tongue 37 and are pivotally 105 connected to lower end portions of the yoke lever 44 at their forward ends and at their rear ends to boxings 58, 59 carried by inner end portions of the forward disk gangs 11, 12. Other links 60, 61 are connected at their 110 forward ends to the yoke lever 44, or preferably to forward portions of the links 56, 57 respectively, and said links 60, 61 are pivoted at their rear ends to inner end portions of the evener bars 13, 14. Oscillation of the 115 yoke lever 44, it will be observed, will also result in oscillation or adjustment of the forward disk gangs, the inner end portions of said gangs being moved in one direction (forwardly or rearwardly) by draft on the 120 130

links 56, 57, while the outer end portions of said gangs are moved in the opposite direction by action of the links 60, 61, evener bars 13, 14 and links 15, 16. By this arrangement the forward disk gangs are moved from both ends, in the process of adjusting their angular relation, and neither end need be moved a great distance to accomplish the end sought. It will also be observed that an oscillation of the yoke lever 44 results in simultaneous adjustment of the gangs of the forward and rear harrows, which adjustment is uniform and in opposite directions with respect to the two harrows and with respect to the two gangs of each harrow, by which the working arrangement illustrated in Fig. 1 may be secured by a single oscillation of said yoke lever. A pitman 62 is pivoted at one end to the upper central portion of the yoke lever 44 and extends rearwardly and downwardly, is forked and embraces and is pivoted by means of a bolt 63 to the draw bar 43. Sliding movement of the draw bar 43 on the stub tongue will effect an oscillation of the yoke lever 44 through the pitman 62 and result in the adjustment of the disk gangs as above described. To normally prevent sliding movement of the draw bar 43 a bell-crank detent 64 is pivoted in a casting 65 carried by the stub tongue and arching over the said draw bar, said detent being pressed by a spring 66 to engagement with one or another of ratchet notches 67 formed in the upper margin of said draw bar. A cord 68 is secured to the upper end of the bell-crank detent 64 and is extended forwardly to a position near the operator's seat on the tractor. Manual draft on said cord results in a release of the detent 64, 40 against the action of the spring 66, so that draft on the draw bar 43, as by forward movement of the tractor, will result in a forward sliding movement of said draw bar, a forward oscillation of the upper end portion 45 of the yoke lever 44 through thrust of the pitman 62, and an adjustment of the disk gangs to angular relation as shown and as previously described. As soon as sufficient angularity of the gangs has been accomplished 50 the cord 68 is released and the spring 66 moves the detent to engaging position, whereupon draft on the draw bar will result in forward movement of the tandem harrow. Rearward movement of the tractor and of the draw bar will result in an opposite movement of the parts and a straightening out 55 of the disk gangs. Stops such as 69 may be provided to limit sliding movement of the draw bar 43 in either direction.

50 The construction and operation hereinbefore described accomplishes an equal or uniform adjustment of each of the gangs. At times it is desirable to secure different angular relation, especially of the forward 55 gangs, as when the machine is operating on a side-hill. To permit a selective adjustment through manual operation I have provided that instead of connecting the links 56, 57 directly to the lower end of the yoke lever 44, hand levers 70, 71 are employed, 70 fulcrumed between their ends on the bolts 45 and arranged just outside of and in contact with the side members of said yoke lever, and the links 56, 57 are connected to lower ends of said hand levers. The hand 75 levers 70, 71 normally are locked to the yoke lever 44 by means of detent devices 72, 73 engaged in internal segment 74, 75 formed on the lower ends of the side members of said yoke lever. Normally the hand 80 levers are arranged in a central position on and locked to the yoke lever so that the automatic power adjustment of the disk gangs may be accomplished as above described; but in case it becomes desirable to 85 secure different adjustments of the forward disk gangs, one or the other of the hand levers 70, 71 may be released by manipulation of its detent devices, and the links 56, 57 and members connected therewith be 90 adjusted manually to the desired extent, and independently of the other of said links. The hand levers 70, 71 preferably are bent 95 decidedly between their ends and inclined forwardly at their upper ends so as to be operable from the seat of the tractor.

The special boxing shown in Figs. 6 to 9 inclusive has been designed particularly to overcome end thrust in the rear disk gangs. The axle 76 of a gang is shown extended 100 through a spool 77 in a common manner, which spool is received in the horizontal bearing of the boxing 19. The spool 77 is formed with a flange 78 or shoulder spaced from the adjacent end of the bearing, and 105 between said flange or shoulder and the end of the bearing are interposed two chilled steel rings, designated by the numerals 79, 80, one of which is locked to the spool and the other to the boxing by means of lugs 81 110 entering notches in said members. The rings are designed to overcome end thrust, and preferably are made in semi-circumferential halves to facilitate assembling and removal for repairs.

115 A cup 82 for lubricant is mounted in a hole in the upper portion of the upper member of the boxing, in a common manner, and a semi-circumferential groove 83 leads from the inner end of this hole, on the inner surface of the bearing, to a point diametrically opposite to said cup, said groove being formed partly in the upper member of the boxing and partly in the lower member, as shown by dotted lines in Fig. 7. A hole 120 84 (dotted lines Fig. 6) leads from the lower end of the groove 83 through the maple bushing 85 of the spool 77, and thus lubricant is supplied to the axle 76 at the free side of its bearing.

125 130

The vertical bearing 22 of the forward extension 21 of each boxing 19 or 20 is of tapered form as shown in Fig. 9, being enlarged laterally at its upper and lower ends but not longitudinally, to permit some freedom of movement of the spindle 24 or 25 therein on lines transversely to the path of travel of the machine, but preventing any play on lines parallel to the path of advance.

Some users may prefer separate manually operable means for independently shifting the gangs of the rear harrow and in this event the links 46, 47 are dispensed with and shorter links such as 86 (see Fig. 10) employed in their stead and connected to hand levers such as 87 fulcrumed at any convenient location on each of the draft links 35 and 36 and provided with detent devices 20 engageable in segments 89 carried by said draft links. When the levers 87 and links 86 are employed, the rear gangs are not adjusted simultaneously with the front gangs through shifting of the yoke 44, but each of 25 the rear gangs is adjusted separately and independently by manual operation, through the hand lever 86 applicable thereto.

My harrow herein shown and described possesses the advantages of the so-called 30 leverless harrows, in the provision for simultaneously and uniformly adjusting all of the gangs through power applied from the tractor; and it possesses a decided advantage in addition thereto in the provision 35 for manual independent adjustment of the forward disk gangs selectively on occasion.

I claim as my invention —

1. In a tandem disk harrow, a leader harrow provided with a frame and a tongue, a 40 trailer harrow provided with a cross frame bar extending substantially throughout its entire length, an evener bar arranged in front of said frame bar, links pivotally connecting extreme outer end portions of said 45 cross frame bar to outer end portions of said evener bar, and draft links connected pivotally at their rear end to outer end portions of said evener bar, said draft links converging substantially together at their 50 forward ends and being pivotally connected to the tongue of said leader harrow and arching over the frame of said leader harrow without any connection thereto.

2. In a tandem disk harrow, a leader harrow provided with a frame and a tongue, a 55 trailer harrow provided with a frame, a plate arranged transversely of and projecting beyond said tongue, clips swiveled in end portions of said plate, and draft links 60 pivotable at their rear ends to outer end portions of the frame of the trailer harrow, arching over and disconnected relative to the leader harrow frame and converging to and being pivotable adjacent each other in 65 the clips on horizontal axes.

3. In a harrow, a frame, a disk gang pivotally secured thereto, said frame including a cross-member arranged in front of said disk gang, a rock shaft journaled in said cross-frame member in front of said disk gang, a 70 link pivotally connecting said rock shaft to one end portion of said gang, and means for oscillating said rock shaft.

4. In a disk harrow, a frame, disk gangs pivotally secured thereto, said frame including 75 a cross-member arranged in front of both of said gangs, a pair of spaced bearings carried by said cross-frame-member on each side of the median line of the frame, a rock shaft journaled in each pair of said bearings, a link pivotally connecting each of said rock shafts to one of said gangs, and means for simultaneously rocking said shafts.

5. In a tandem harrow, a leader harrow 85 including a frame and disk gangs pivoted thereon, a trailer harrow including a frame and disk gangs pivoted thereon, draft links pivotally connecting the trailer harrow to the leader harrow, means for simultaneously 90 and uniformly shifting all the gangs of both of said harrows to adjust their angularity relative to the path of advance of the machine, and independent means for shifting 95 certain of said gangs.

6. In a tandem disk harrow, a leader harrow including a frame and disk gangs pivoted thereto, a trailer harrow including a frame and disk gangs pivoted thereto, draft links pivotally connecting the trailer harrow to the leader harrow, means for simultaneously and uniformly shifting the gangs 100 of both of said harrows to adjust their angularity relative to the path of advance, and independent means for selectively shifting 105 the gangs of the leader harrow.

7. In a tandem disk harrow, a leader harrow including a frame and disk gangs pivoted thereto, a trailer harrow including a frame and disk gangs pivoted thereto, draft 110 links pivotally connecting the trailer harrow to the leader harrow, a member adapted for sliding movement on the leader harrow and adapted to be connected to a tractor device, means connected with said sliding member for simultaneously and uniformly shifting all of the gangs to alter 115 their angularity relative to the line of advance, and manually operated means for independently adjusting the angularity of the 120 gangs of the leader harrow.

8. In a tandem disk harrow, a leader harrow including a frame and disk gangs pivoted thereto and a tongue on said frame, a trailer harrow including a frame and disk 125 gangs pivoted thereto, draft links pivotally connecting the trailer harrow to the leader harrow, a draw bar adapted for sliding movement on said tongue and adapted to be connected to a tractor device, means for 130

- latching said draw bar against sliding movement, means connecting said draw bar to each of the disk gangs whereby sliding movement of the former is transformed to pivotal shifting movement of the latter, and separate means or manually and independently adjusting the gangs of the leader harrow.
9. In a disk harrow having disk gangs mounted for pivotal movement on vertical axes, means for shifting said gangs comprising a member mounted for sliding movement and adapted to be connected to a tractor device, means for latching said sliding member against movement, a lever pivotally mounted and having pivotal connections to said sliding member, links connecting said lever to the respective disk gangs, and means for shifting certain of said gangs independently of said lever means.
10. In a disk harrow having disk gangs mounted for pivotal movement on vertical axes, means for shifting said gangs comprising a draw bar adapted for sliding movement and adapted to be secured to a tractor device, means for latching said draw bar against sliding movement, a lever pivotally mounted and having pivotal connections to said sliding member whereby said lever is oscillated through sliding movement of said draw bar, hand levers fulcrumed on said lever and adapted for independent adjustment at times and adapted normally to be locked thereto, and links pivotally connecting said hand levers to said disk gangs, whereby said gangs may be simultaneously and uniformly shifted through operation of said draw bar or be independently shifted manually by operation of said hand levers.
11. In a disk harrow, a frame, a tongue thereon, disk gangs pivotally secured to said frame, a draw bar mounted for sliding movement on said tongue and adapted to be secured to a tractor device, means for latching said draw bar against sliding movement, a lever fulcrumed on said tongue, a pitman 45 pivotally connecting said draw bar to said lever, said yoke lever being formed with a pair of segments, hand levers suitably fulcrumed and having detent devices by means of which they may be latched to the segments of said lever, and links pivotally connecting said hand levers to said disk gangs.
12. In a tandem disk harrow, a forward frame, disk gangs pivoted thereon, a rear frame, disk gangs pivoted thereon, rock 55 shafts journaled in the rear frame, pivotal connections between said rock shafts and the gangs of the rear frame, draft connections between the rear and forward frames, a draw bar slidably mounted on the forward 60 frame and adapted to be secured to a tractor device, means for latching said draw bar against sliding movement, a member fulcrumed between its ends on said forward frame, pivotal connections between said 65 member and the draw bar for oscillating said member through sliding movement of said draw bar, means pivotally connecting one end of said member to the respective rock shafts, hand levers fulcrumed on and 70 adapted to be latched to said member, and pivotal connections between said hand levers and the gangs of the forward frame.
13. In a disk harrow, a frame member, a vertical spindle carried by said frame member, a disk gang having a boxing adjacent one end thereof, said boxing being formed with a vertical bearing to receive said spindle, said bearing being enlarged laterally at its upper and lower ends to permit 75 some freedom of movement of said spindle on lines transversely to the path of advance of the device, and means for shifting said disk gang on the axis of said spindle.
- Signed at Des Moines, in the county of 85 Polk and State of Iowa, this 21st day of May, 1920.

FRANK H. FRENCH.
